UNITED STATES PATENT OFFICE

SALIM N. MALLOUK, OF BROOKLYN, NEW YORK

DESIGN FOR AN EMBROIDERED BRIDGE-TABLE COVER OR THE LIKE

Application filed June 6, 1929. Serial No. 31,562. Term of patent 3½ years.

To all whom it may concern:

Be it known that I, SALIM N. MALLOUK, a citizen of the United States of America, and a resident of the borough of Brooklyn, Kings County, city and State of New York, have invented a new, original, and ornamental Design for Embroidered Bridge-Table Cover or the like, of which the following description, in connection with accompanying drawing, is a specification.

The single figure of the drawing is a plan view of one-fourth of an embroidered bridge table cover or the like, showing my new design. The design shown in the representative illustration is repeated in the other three corners.

I claim as my invention:

The ornamental design for an embroidered bridge table cover or the like as shown and described.

SALIM N. MALLOUK.
